UNITED STATES PATENT OFFICE.

WILLIAM H. RICHARDSON, OF JERSEY CITY, NEW JERSEY.

WEB-OPERATING MECHANISM.

1,001,445.

Specification of Letters Patent. Patented Aug. 22, 1911.

Application filed October 5, 1910. Serial No. 585,358.

To all whom it may concern:

Be it known that I, WILLIAM H. RICHARDSON, a citizen of the United States, residing in the city of Jersey City, county of Hudson, 5 and State of New Jersey, have invented certain new and useful Improvements in Web-Operating Mechanism, of which the following is a full, clear, and exact specification.

This invention relates to web operating 10 mechanism and has for its object to provide simple and efficient mechanism for intermittently adjustably accelerating the forward speed of a web.

The improvement is peculiarly adapted 15 for use on a printing press in which the centers of the impressions are to be spaced farther apart than the circumference of the printing cylinder. When such employment is in a cylinder press for printing a web 20 from which sheet lengths are to be cut the amount of acceleration may be varied for enabling a single roller or printing cylinder to do duty in connection with sheets of many lengths, for instance a printing roller of a 25 given diameter may be employed for printing upon a web for making sheets of a length equal to the circumference of the roller or of any much greater length which is desired.

30 In the drawings accompanying and forming a part of this specification Figure 1 illustrates diagrammatically the end view of a web printing press equipped with my present improvement. Fig. 2 is an enlarged 35 detail of one of the guide rollers and the accelerating mechanism, Fig. 3 is a cross section of the device illustrated in Fig. 1, showing the adjustability of the accelerators, Fig. 4 is an enlarged detail view of 40 the feed cylinder and cutting devices.

A web of material 5, which web may, if desired, be cloth, will be fed into the machine from some suitable source and will pass over suitable guide-rollers and pass between the printing-cylinder 6 and the platen-cylinder 7, and through and over other guide-rollers to the feeding and cutting mechanism 8. The feeding and cutting mechanism engages and draws forward the 45 web and cuts the same into sheets of predetermined length, and it may be adjusted as occasion demands for determining the length of the sheets. The feeding and cutting mechanism herein illustrated comprises a 50 cylinder composed of two halves 20, 20,

which are adjustable one toward the other and may have suitable engaging prongs or projections of any desired construction indicated by the numeral 20^a, adapted to engage the web and hold the same in contact with the cylinder parts. Toggles 21, and adjusting-screws 22, are provided for the purpose of effecting the relative adjustment of the cylinder halves. The cutter proper herein illustrated is a saw 65 25, caused to travel within the cylinder by any suitable means. The saw is located partly within the cylinder and protrudes through the openings 27, between the cylinder halves. The travel of the cutter is so timed that it will cut the fabric behind one of the rows of holding pins on the cylinder and in front of the other row. The web will always be engaged by one of the rows 70 of pins and at times by both rows. 75

The printing cylinder 6 is shown provided with a raised printing-surface 9, and a plane-surface 10, so that its circumference is divided between a printing-surface and a plane-surface. The cylindrical platen 7 is 80 disposed at a sufficient distance from the printing cylinder 6, that the printing surface 9 will properly act upon the web 5 passing between the cylinders at the time the printing-surface is opposed to the platen, 85 and that at the time the plane-portion 10 is presented in opposition to the platen, there will be sufficient space between the cylinders to permit the web to move at a different speed than the surface speed of the cylinders. 90

If the call of the feeding-device 8 is such that the web will pass with the surface speed of the cylinders 6, the roller 12 will be held from rotation and the web permitted to pass over the plane-portion 10 of the cylinder and the shaft 12. When, however, the call of the feeding-device is in excess of the normal delivery of the printing-cylinder 6, the web must be accelerated between impressions an amount sufficient to satisfy the call of the feeding-device. As the web is passed across the printing-cylinder, it will be permitted to move at the same surface speed as the printing-surface-portion 9, while this printing-surface-portion is in its printing position. After the printing-surface-portion has all run over the web, the web will then be given an accelerated movement and drawn across the plane-surface 10 of the 100 105 110

printing-cylinder, in the present illustration by means of series of web-engaging devices carried by the shaft 12.

The shaft 12 is driven in proper sequential timing with the feeding-device 8 and is shown having a pair of adjustable brackets 13, which are shown provided with radially-disposed ways 14, for receiving the ends 15, of bars 16. The bars are the members which will engage the web to accelerate its feed. The ends 15 are adjustable in the ways 14. They will be held in their positions of adjustment by some suitable means, as for instance, tap-bolts 17. By means of the radial adjustment of the members 16 toward or away from their axis of revolution—that is, the axis of the shaft 12—the amount of acceleration given the web may be adjusted so that the intermittent accelerations will be equal to the difference between the circumference of the printing cylinder 6 and the distance between the centers of the printed matter on the web.

The printing-cylinder 6, the shaft 12, and the cutting-and-feeding-device 8, are shown geared together by a suitable train of gearing which will cause these parts to move in unison.

Although I have shown but one form of mechanism for carrying out my improvement, yet changes may be made within the scope of my invention without departing therefrom.

Having thus described my invention what I claim and desire to secure by Letters Patent is:

1. The combination with a cylinder having a printing surface on a portion only of its perimeter, of severing mechanism, and means interposed between the printing cylinder and severing mechanism including means for guiding a web away from such cylinder and adjustable means associated with a member of the said guiding means for accelerating the web movement between impressions.

2. The combination with a roller having its perimeter divided into a printing surface and a plane surface, of severing mechanism, means for passing a web across said roller and rotatable means interposed between the printing surface and severing mechanism and adapted to engage the web for accelerating the feed of the web while passing over the plane portion.

3. The combination with a cylinder hav-

ing its perimeter divided into a printing surface and a plane surface, of means for passing a web across said cylinder and comprising a small guide roller and web-engaging members carried by said roller at one side thereof.

4. The combination with a cylinder having its perimeter divided into a printing surface and a plane surface, of means for passing a web across said cylinder and comprising a small guide roller and web-engaging members carried by said roller and means for radially adjusting said members.

5. The combination with a printing cylinder and a platen cylinder, the printing cylinder being provided with a raised printing surface and a plane surface, said plane surface being located in position to make a clearance with the platen cylinder, of a circumferentially-adjustable web feeding device and a cutting device, a guide roller between the web feeding device and the printing cylinder and provided with a portion of small radius and a portion of larger radius, and gearing between said web feeding and cutting devices and the printing cylinder and the said guide roller for causing these parts to move in unison and for causing the portion of greater radius of the guide roll to engage the web while this is in engagement with the plane surface of the printing cylinder.

6. The combination with a printing cylinder provided with a printing surface upon a portion of its perimeter and a plane surface upon another portion thereof, of an auxiliary cylinder, circumferentially adjustable, a guide roller for the web comprising a portion of small radius and a plurality of members carried thereby and making a surface of greater radius, means for adjusting the radial distance of said members from said roller, means connecting said printing cylinder, auxiliary cylinder and guide roller together, to move in unison, irrespective of the adjustment of said adjustable members and timed for bringing the same into engagement with the web while this is passing over the plane surface of the cylinder.

In witness whereof I have hereunto set my hand in the presence of two subscribing witnesses.

WILLIAM H. RICHARDSON.
